CLAIM

The ornamental design for a side frame for modular furniture substantially as shown and described.

DESCRIPTION

FIG. 1 is a front view of a side frame for modular furniture of a first embodiment;

FIG. 2 is a rear view of the side frame of FIG. 1;

FIG. 3 is a top view of the side frame of FIG. 1;

FIG. 4 is a bottom view of the side frame of FIG. 1;

FIG. 5 is a left view of the side frame of FIG. 1;

FIG. 6 is a right view of the side frame of FIG. 1;

FIG. 7 is a left perspective view of the side frame of FIG. 1;

FIG. 8 is a right perspective view of the side frame of FIG. 1;

FIG. 9 is a perspective view of the side frame for modular furniture of FIG. 1, shown in a state of use;

FIG. 10 is a front view of a second embodiment of a side frame for modular furniture;

FIG. 11 is a rear view of the side frame of FIG. 10;

FIG. 12 is a top view of the side frame of FIG. 10;

FIG. 13 is a bottom view of the side frame of FIG. 10;

FIG. 14 is a left view of the side frame of FIG. 10;

FIG. 15 is a right view of the side frame of FIG. 10;

FIG. 16 is a left perspective view of the side frame of FIG. 10;

FIG. 17 is a right perspective view of the side frame of FIG. 10;

FIG. 18 is a perspective view of the side frame for furniture of FIG. 10, shown in a state of use;

FIG. 19 is a front view of a third embodiment of a side frame for modular furniture;

FIG. 20 is a rear view of the side frame of FIG. 19;

FIG. 21 is a top view of the side frame of FIG. 19;

FIG. 22 is a bottom view of the side frame of FIG. 19;

FIG. 23 is a left view of the side frame of FIG. 19;

FIG. 24 is a right view of the side frame of FIG. 19;

FIG. 25 is a left perspective view of the side frame of FIG. 19;

FIG. 26 is a right perspective view of the side frame of FIG. 19;

FIG. 27 is a perspective view of the side frame for modular furniture of FIG. 19, shown in a state of use;

FIG. 28 is a front view of a fourth embodiment of a side frame for modular furniture;

FIG. 29 is a rear view of the side frame of FIG. 28;

FIG. 30 is a top view of the side frame of FIG. 28;

FIG. 31 is a bottom view of the side frame of FIG. 28;

FIG. 32 is a left view of the side frame of FIG. 28;

FIG. 33 is a right view of the side frame of FIG. 28;

FIG. 34 is a left perspective view of the side frame of FIG. 28;

FIG. 35 is a right perspective view of the side frame of FIG. 28; and,

FIG. 36 is a perspective view of the side frame for modular furniture of FIG. 28, shown in a state of use.

The broken lines shown in the drawings are for illustrative purposes only and form no part of the claimed design.
